UNITED STATES PATENT OFFICE.

ADRIAN C. COOKE, OF CHICAGO, ILLINOIS, ASSIGNOR TO ILLINOIS METALLIC NOVELTY COMPANY, OF CHICAGO, ILLINOIS, A CORPORATION OF ILLINOIS.

DESIGN FOR A TOY-VEHICLE BODY.

44,299.

Specification for Design.

Patented July 8, 1913.

Application filed April 3, 1912. Serial No. 688,312. Term of patent 3½ years.

To all whom it may concern:

Be it known that I, ADRIAN C. COOKE, a citizen of the United States, residing at Chicago, in the county of Cook and State of Illinois, have invented a new, original, and ornamental Design for Toy - Vehicle Bodies, of which the following is a specification, reference being had to the accompanying drawing, forming part thereof.

The figure is a perspective view of a vehicle body, showing my new design.

I claim:

The ornamental design for a toy vehicle body, as shown.

ADRIAN C. COOKE.

Witnesses:

GEORGE E. MUELLER,
CARRIE E. ANDERSON.
